UNITED STATES PATENT OFFICE.

WILLIAM FREDERICK COTTRELL, OF BRISTOL, ENGLAND.

SHAVING-STICK HOLDER.

Application filed May 15, 1922. Serial No. 561,040.

To all whom it may concern:

Be it known that I, WILLIAM FREDERICK COTTRELL, a subject of the King of Great Britain and Ireland, and residing at 435
 5 Fishponds Road, Fishponds, Bristol, in the county of Gloucester, England, have invented certain new and useful Improvements in and Relating to Shaving-Stick Holders, of which the following is a specification.

This invention relates to shaving stick holders of the type comprising a container and a sliding member therein supporting the soap and having means projecting 15 through longitudinal slots in the container whereby the sliding member may be adjusted longitudinally according to the length of the soap stick.

The invention comprises a container having longitudinal and lateral slots, a sliding member having means engaging said slots and adapted to carry the shaving stick and spring means for holding the sliding member in its adjusted relation. Said spring 25 means may comprise an S-shaped spring attached to the sliding member the ends of the spring engaging the slots in the container.

The accompanying drawings illustrate diagrammatically the carrying of the invention into effect:

Figure 1 is an outside elevation of a holder according to one form;

Figure 2 being a sectional elevation thereof;

Figure 3 is an elevation of a modified form;

Figure 4 is a sectional plan of a detail;

Figures 5 and 6 are sectional elevation and plan of a further form.

In carrying the invention into effect as shown in Figures 1 and 2, a cylindrical container 7 is provided having diametrically opposite slots 8 arranged longitudinally and extending to within about a quarter of an 40 inch from either end.

Connected to said slots are a series of lateral slots 9. These slots 9 are arranged throughout the length of the longitudinal slots and at a suitable distance apart. The 50 lateral slots extend either side of the longitudinal slots or, if desired, they may extend only on one side of the longitudinal slots, as indicated in Figure 3.

Sliding within the cylindrical container 7 is a member 10 adapted to hold the shav-

ing-stick 11. This member is provided with pins 12 mounted at diametrically opposite points, such pins being adapted to project through the slots in the container.

If desired, milled heads 13 or the like 60 may be mounted on said pins 12 in order to facilitate the manipulation of the device.

It will be understood that according to the length of the shaving-stick 11 the sliding member 10 may be adjusted longitudinally 65 and rotated so that the pins 12 engage in the appropriate lateral slots 9. Spring means comprising blade spring 16 riveted to the member 10 at diametrically opposite points are provided for holding the member 70 10 in its adjusted position.

The upper end of the container is provided with a closing cap 14 which may be screwed thereon or may slide thereon as desired or be fixed in any other suitable manner.

In order to strengthen the container 7, which may be weakened by the cutting therein of the slots, longitudinal ribs or corrugations 15 may be provided adjacent 80 the slots as indicated in Figure 4.

The spring means which are provided to hold the sliding member 10 in its adjusted position may comprise, as illustrated in Figures 5 and 6, an S-shaped spring 16 85 mounted on the sliding member 10 so that the ends 17 thereof engage in the lateral slots, so that by an inward pressure on such ends by means of the milled heads they may be disengaged from the lateral slots 90 while on releasing them after longitudinal adjustment the ends of the spring will engage in other slots and hold the sliding member rigidly in position.

Having now described my invention what I claim as new and desire to secure by Letters Patent is:—

1. A shaving stick holder comprising a container having longitudinal and lateral slots, a sliding member inserted in said container, spring means comprising an S-shaped spring attached to said sliding member, the ends of said spring engaging said slots.

2. A shaving stick holder as claimed in claim 1, wherein buttons are mounted on the ends of said spring.

In testimony whereof I have signed my name to this specification.

WILLIAM FREDERICK COTTRELL.
